AUTOMATIC STOKER

Emil C. Schneider, South Bound Brook, N. J.

Application May 12, 1945, Serial No. 593,395

7 Claims.

(Cl. 110—36)

The present invention relates to automatic stokers for coal-burning furnaces and more particularly to a coal stoker of a simple, trouble-free design.

Existing stokers have certain well-recognized drawbacks which detract considerably from their otherwise comparatively satisfactory design and operation. Some of these drawbacks include the inability to handle all the various common types of solid fuel, failure to remove ash completely, lack of effective control over the fuel level in the furnace, lack of provision for preventing jamming of and damage to the equipment due to oversize pieces of fuel or fuel overfeed and general inflexibility to varying conditions encountered during operation or for different installations. So far as I am aware these drawbacks have not heretofore been overcome.

It is, accordingly, one of the objects of my present invention to provide an automatic coal stoker which overcomes the defects and disadvantages of prior stokers and which has new and useful features of unique nature.

Another object of the invention resides in the provision of a stoker which is capable of handling anthracite and bituminous coal as well as coke of various sizes.

A further object of the invention resides in a stoker having a segmented grate from each segmental section of which ash can be completely removed.

A still further object of the invention is to produce a stoker which will allow for the handling of oversize pieces of fuel without jamming or damaging the equipment and which is so designed as to give effective control over the fuel level in the furnace.

Other and further objects and advantages will be understood by those skilled in this art or will be apparent or pointed out hereinafter.

In the accompanying drawings wherein I have illustrated a preferred embodiment of my invention:

Fig. 1 is a plan view of my new automatic coal stoker;

Fig. 2 is a sectional view through the stoker along the line 2—2 of Fig. 1;

Fig. 3 is a front elevational view of the stoker of Fig. 1 with parts broken away to expose the interior construction;

Fig. 4 is a schematic view taken along line 4—4 of Fig. 2 and Fig. 5 is a side elevational view of a complete stoker unit with parts broken away to expose the construction of the fuel feeding ram.

Like numerals designate corresponding parts throughout the various views of the drawings.

Referring now to the drawings in detail, the numeral 10 indicates the fuel feeding ram which is adapted to be reciprocated within the elongated housing 11. The upper surface of ram 10 is saw-toothed or serrated and acts to push incrementally into the stoker proper solid fuel fed thereto through hopper 12. Reciprocation of ram 10 is effected in any suitable manner as by the eccentric drive means designated by the numeral 13. Housing 11 extends substantially to the center of the cylindrical housing 14 which is supported within a furnace (not shown) of any suitable kind and construction the details of which per se form no part of this invention. The inner end of housing 11 is provided with a hinged fuel regulating door 15 which swings outwardly to enable oversized pieces of fuel to be discharged without jamming or causing damage to the stoker or its appurtenances. Door 15 is heavy enough (thickened or counterweighted at its lower edge if additional weight is desired) to level off the supply of fuel and ensure substantial uniformity of fuel feed, the quantity of which per unit of time is adjustable by changing the vertical positioning of the door by the turning action of pinion 16 on racks 17 to which the door is attached. Suitable vertical guides 18 are provided for the door 15 as shown. It will be clear that the higher the door is raised the greater will be the amount of fuel fed. The position of the door is regulated according to the nature of the fuel and the heating effect to be produced. Pinion 16 is turned by means of shaft 19 mounted in and supported by hangers 20.

Axially disposed on the floor 21 of the cylindrical housing 14 is a socketed boss 22 into which revolvably fits the downward extension 23 of post 24. The diameter of post 24 is, however, somewhat less than that of the upper end of the tapering boss 22 thus providing an annular shoulder 25 one portion of which is cut away at 26 for a reason to be explained. Within housing 14 is also a spider which is comprised of a rim 27 and spokes 28 connected to post 24 which serves as the hub. Rim 27 has a cross-section in the form of an inverted L, the lower edge of which is formed as a circular rack or gear meshing with bevel gear 29 which is fixed on the shaft 30 projecting through a bushing provided at a suitable location in the side of housing 14. Shaft 30 is slowly rotated by any suitable source of power such as a low speed or geared-down electric motor (not illustrated). A grate member 32 of seg-

mental shape is mounted between adjacent spokes 28, six such grate members being illustrated. The exact number may, however, vary and thus is intended to constitute no limitation upon the invention. Grates 32 are made of cast iron or any other suitable or conventional material and are each provided with a pair of trunnions 33 by means of which the grates are revolvably mounted. Each inner trunnion projects into a recess in post 24 provided for that purpose and each outer trunnion extends through a hole in rim 21, terminating in a dumping gear 34. A dumping gear rack 35 is integrally secured to the inner surface of housing 14 opposite cut-away portion 26 above referred to.

Each grate is provided with a plurality of projections 36 and apertures 37 arranged in a suitable pattern to prevent dense packing of the fuel and to provide draft, respectively. From Fig. 2 in particular it will be observed that grates 32 have their inner edges resting on shoulder 25 and, therefore are normally held in operative (non-dumping) position. As rim 21 slowly rotates the grates successively reach rack 35 and cut-away portion 26 at which time each dumping gear 34 meshes with the rack 35 to turn each grate through an angle of 180 degrees, such turning being permitted by cut-away portion 26. Rack 35 is thus equal in length to one-half the circumference of gears 34 but I may, if I so desire, provide a rack equal to the complete length of the circumference of gears 34 to cause the grates 32 to make a full turn of 360 degrees. This is not usually necessary, however, particularly where the grates are symmetrical on both sides. During the grate turning movements the contents are dumped and the grate surface made ready for a new fuel charge. The dumping operation described ensures the removal of all ash, clinker, etc. and thus overcomes one of the serious defects of previous types of stokers. Since the dumping arrangement provides adequate discharge spaces (observable from Fig. 1 which shows one grate in vertical position), ash or clinker, etc. cannot be caught or retained on the grate and cannot cause jamming or damage during the grate turning movement. Each grate is dumped once each rotation of rim 21 as will be understood. The rate of movement of rim 21 is slow enough to enable the fuel to be efficiently consumed in slightly less than a complete rotation. The ash, clinker, etc. dumped from the grates travels down through a removal chute 38 to a receptacle or to any desired point of discharge. Numeral 39 indicates an air inlet to ensure proper combustion conditions for effective utilization of the fuel.

A stoker constructed in accordance with my invention is characterized by being able to burn various types of fuel in which connection it will handle anthracite coal, bituminous coal and coke or combinations or mixtures thereof in sizes varying from barley to chestnut. Due to its construction there is no possibility of obnoxious fumes passing through the fuel hopper but any such fumes must go out through the furnace flue. The

hopper 12 and casing 11 are sealed off by the fuel therein so that fumes cannot readily traverse the same and at the same time the ram is so designed that it will slide under the fuel whenever there is sufficient fuel already in feeding position in contrast to the screw type of fuel feeder which continues to force fuel ahead whether needed or not thus often causing jamming and breakage. The ram shown thus eliminates overfeeding and wasting of fuel as well as preventing damage.

It is nevertheless to be understood that the foregoing is intended as illustrative and not as limitative and that other and further additions, omissions, substitutions and modifications may be made without departing from the spirit or principle hereof. The invention is rather that defined by the subjoined claims.

I claim:

20. 1. A stoker comprising a cylindrical housing, a spider revolvably mounted in said housing, a plurality of segmental grates rotatably mounted in said spider, means to revolve said spider slowly and means to rotate each segmental grate for dumping purposes at a predetermined point in its path of revolution.
25. 2. A stoker as claimed in claim 1 in which the spider is comprised of a rim the lower edge of which is a circular rack and the spider revolving means includes a bevel driving gear in mesh with the circular rack aforesaid.
30. 3. A stoker as claimed in claim 1 in which each segmental grate is trunnion mounted, one of the trunnions being provided with a dumping gear adapted to be turned by a dumping rack mounted in the cylindrical housing.
35. 4. A stoker as claimed in claim 1 provided with a ram for feeding fuel to said grates, a housing for said ram and a fuel hopper in said housing.
40. 5. A stoker as claimed in claim 1 in which means is provided for feeding fuel evenly and at an adjustable rate to said grates, said means including an elongated housing radially disposed with respect to said cylindrical housing, a reciprocable fuel moving ram operable within the elongated housing and a vertically adjustable weighted door hingedly mounted at the inner end of said elongated housing.
45. 6. In a stoker of the character described, a cylindrical housing, a spider in said housing and segmental grates in said spider, each of such grates being mounted on trunnions and coating gear and rack means on certain of said trunnions and on said housing for turning said grates through an angle of at least 180 degrees.
50. 7. In a stoker of the character described, a cylindrical housing and a socketed boss rising from the bottom of said housing the upper surface of which constitutes an annular shoulder one portion of which is cut away to form a recess, a spider having a hub extension in the socket of said boss, a dumping rack secured to said housing, segmental grates trunnioned in said spider and a dumping gear for each grate adapted to coact with said dumping rack.

EMIL C. SCHNEIDER.
